Customerized Optical Grade PMMA LED Flashlight Lens Plastic Mould. By Made-inChina.com. Dated Apr. 25, 2019. Found online [Sep. 16, 2021]. <https://sumshun.en.made-in-china.com/product-SsEmNGulZXhb/China-Customerized-Optical-Grade-PMMA-LED-Flashlight-Lens-Plastic-Mould.html> (Year: 2019).*

Primary Examiner — Marissa J Cash*Assistant Examiner* — William B Melliar(74) *Attorney, Agent, or Firm* — Garson & Gutierrez, PC(57) **CLAIM**

The ornamental design for a lens for flashlights, as shown and described.

DESCRIPTION

FIG. 1 is a perspective view of a lens for flashlights, showing our new design;

FIG. 2 is a rear perspective view of the lens of FIG. 1;

FIG. 3 is a front side elevation view of the lens of FIG. 1;

FIG. 4 is a back side elevation of the lens of FIG. 1;

FIG. 5 is a left side elevation view of the lens of FIG. 1;

FIG. 6 is a right side elevation view of the lens of FIG. 1;

FIG. 7 is a top plan view of the lens of FIG. 1;

FIG. 8 is a bottom plan view of the lens of FIG. 1; and,

FIG. 9 is a cross-sectional view of the lens of FIG. 1, taken along line 9-9 as shown in FIG. 3.
